UNITED STATES PATENT OFFICE.

CHARLES W. STIGER, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,306,031.

Specification of Letters Patent. Patented June 10, 1919.

Application filed July 12, 1915. Serial No. 39,212.

To all whom it may concern:

Be it known that I, CHARLES W. STIGER, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a part of this specification.

My invention relates to carbureters for internal combustion engines, and has for its object improved means for creating and maintaining the most desirable mixture proportions for the varying demands of the engine with which the device is connected.

In that type of carbureter wherein the feed of gasoline is due to aspiration, there is a difficulty which is due to the fact that upon low suction the reduction in pressure is sufficient to lift the liquid hydrocarbon, which is used for fuel, out of the fuel nozzle, which is provided, but is insufficient to take all of this fuel to the engine. The result is that the supply of the liquid hydrocarbon, such as gasoline, is insufficient on starting and low running so far as that which actually goes to the engine is concerned, while, as a matter of fact, the amount of fuel really lifted out of the nozzle would be sufficient. This gasoline which is lifted out of the nozzle, but which does not get to the engine, settles on the sides of the carbureting chamber and collects where opportunity affords, and then, when the higher suctions are obtained, this collected fuel goes to the engine with the regular supply from the nozzle, making the supply of gasoline on the higher suctions too great. This detrimental action is commonly called "loading."

My invention is concerned with means for properly vaporizing all of the gasoline which is lifted out of the nozzle, on the low suctions, as well as on the high suctions, and it is thus calculated to properly vaporize the gasoline at all suctions and to eliminate the difficulty which has been described.

The means which I provide to carry out the above purpose, may be utilized further in supplying a desired excess of gasoline which shall be available on starting and accelerating. These results are accomplished by providing one or more passage-ways leading from the carbureting chamber,

where gasoline may collect, to the interior of the air passageway through which air enters the carbureting chamber. Since this passageway is properly restricted, it follows that the pressure in the passageway will be less than that in the carbureting chamber and there will thus be a potential tending to move the collected gasoline in the carbureting chamber to the interior of the air passage where it is picked up, vaporized and carried on to the engine. Since the collection of gasoline may occur during periods immediately preceding a beginning or an increase in suction, it will be seen that any accumulation will be utilized to augment the regular flow from the nozzle at such desirable times and for a limited temporary period.

My invention is illustrated in the accompanying drawings in which—

Figure 1 is vertical axial sectional view of the carbureter of my invention;

Fig. 2 is a cross sectional view taken on the plane of the line 2, 2, and looking in the direction of the arrows on Fig. 1; and

Fig. 3 is a detail view illustrating a modified form of my invention.

The main casing is illustrated at 1, and it will be seen that it is interiorly provided with a Venturi tube 2, to which a main air inlet passage-way 3, leads. A manually operated valve 3^a controls this opening. The reference character 4, indicates the carbureting chamber generally, into which the Venturi tube extends, and from which the outlet 5 is provided, this outlet being controlled by the usual throttle valve 6. As illustrated, the casing is provided with the flange 7 by means of which the carbureter is attached to the engine manifold. A water jacket 8 is provided, as shown.

The main fuel nozzle 9 is mounted in a vertical stem 10, which is formed integrally with a bridge 11, extending diametrically across the main air inlet passage. A shelf 12 supports a float chamber 13, which communicates with the nozzle 9 by means of a passage 14, and this float chamber maintains a level of liquid fuel approximately on the dot and dash line x—x, being supplied through the pipe 15.

The carbureting chamber 4 is provided with a side extension 16 in the top wall of which an opening 17 is provided. An annulus 18 is secured in said opening, and a

bridge-piece 19 spans this annulus. The opening through this annulus is the auxiliary air opening.

A hollow stem 20 is hung from a head 21, which rests upon the top of the bridge-piece 19. The bottom of this stem is provided with a collar 21', and a spiral spring 22 rests upon this collar. A valve 23 is provided with a hollow stem 24, which surrounds the stem 20 and at the top of the stem 24 there is provided an adjusting cup 25, within which the spring 22 engages. It will be seen now that the valve 23 is normally held upon its seat by means of the spring 22, and that the tension of this spring may be varied by turning the cup 25, this cup being held in any adjusted position by a snap spring 26, which is carried by the valve, and which engages in any one of a plurality of grooves 27 in the periphery of the cup. Rotation of the valve is prevented by the engagement of a pin 28 in a socket 29 in the part 19.

The hollow stem 24 extends downwardly through an alined opening 25^a in the lower wall of this part of the carbureting chamber, and passes into a dash pot 26^a alined therewith, the bottom of this dash pot being closed by the cap 27^a.

A plunger 28^a, arranged to reciprocate in the dash pot 27^a, is secured to the bottom of the hollow stem 24 by means of a clamping screw 29^a, there being a clearance around the plunger. The interior of the dash pot communicates with the passageway 14 by means of the passageway 30, which enters the dash pot just above the plunger 28^a, as shown.

A supplementary fuel nozzle 31 is inserted in the hollow stem 24 in a position in proximity to the fuel level line, as illustrated. This nozzle is fed through the hollow stem by way of the side passageways 32. It will now be seen that gasolene can travel upwardly from the dash pot, through the hollow stem 24, through the nozzle 31, through the clearance 21^a, around the collar 21' on the stem 20, and through the annular space in which the spiral spring 22 is disposed. A fuel inlet port 33, which is carried on the under side of the valve 23 and is directed toward the outlet from the carbureting chamber, communicates directly with this annular space, as shown.

A normally seated fuel valve 34 extends from a stem 35, which is disposed in the hollow stem 20. A spiral spring 37 surrounds the stem 35 within the hollow stem 20, and tends to keep the valve 34 seated in the nozzle 31.

The stem 35 extends upwardly beyond the head 21 and has at its end a head 36. It will be seen that this is a very flexible arrangement, since the fuel valve 34 may thus be made to be either normally seated or normally unseated. I have illustrated it as

being normally seated, and it will be noted that when the valve 34 opens, the time at which the fuel nozzle opens will depend upon the relation of the head 36 and the head 21. Thus, if it is desired to have the valve 34 open a short distance before the nozzle 31 is opened, the head 36 is so adjusted that normally it is a short distance above the head 21, as illustrated in the drawing. In such a case, it will be seen that under the influence of the spring 37, and gravity for that matter, the valve 34 will follow the downward movement of the nozzle 31 until the head 36 engages with the head 21 and, from then on, the nozzle 31 will be gradually opened wider as its downward movement continues.

Having thus generally described the carburetor structure in which I embody the features of my invention as an instance of their employment, I return now to a consideration of the Venturi tube 2 and the directly associated parts. It will be seen that the casing 1 is provided, in the form shown in Fig. 1, with an opening *a* forming part of the main air passageway. In this opening *a* a ring or bushing *b* is closely fitted, this ring or bushing resting upon a shoulder *c* at the bottom of the opening. The Venturi tube member is provided with a peripheral groove *d*, which is formed between a lower collar *e* and an upper collar *f*. The lower collar fits snugly within the bushing or ring *b* and the upper collar in part does likewise, the upper portion of the upper collar, however, forming a shoulder *g* which rests upon the top of the bushing *b*. In this way the Venturi tube is definitely and firmly supported in position. A plurality of apertures *h*, *h*, extend vertically through the collar *f*, as illustrated in Fig. 2, as well as in Fig. 1, and these apertures, as will be seen, connect the carbureting chamber with the peripheral groove *d*. By means of radial openings, *i*, *i*, the peripheral groove *d* is connected with the interior of the Venturi tube 2 at its most restricted portion. It will now be seen that gasolene lifted out of the main nozzle 9 may be carried up through the Venturi tube on low suctions but once in the carbureting chamber where the suction effect is less, will not go to the engine, but will drop and collect on the walls of the carbureting chamber, ultimately finding its way to the floor of that chamber. The pressure at the top of the openings *h*, *h*, is greater than the pressure at the openings *i*, *i*, due to the restriction of the air passage and due particularly when a Venturi tube is employed to the restriction of the tube, this being as shown in the most restricted portion thereof, and it follows that there will be a movement of the collected gasolene downward through the openings *h*, *h*, into the peripheral groove *d* and inward through the openings *i*, *i*, the

gasolene being thus fed to the incoming air at the point of highest suction. The result is a complete vaporization of the gasolene, and the potential which causes this flow is 5 a continual one while the engine is running under circumstances which need correction.

In this way, the carbureting chamber is kept free from a detrimental collection and the consequent loading and the gasolene 10 which is brought down through the openings h and through i is utilized to augment the gasolene from the nozzle. This condition prevails on low suction, as has been described, and when the throttle is suddenly 15 opened a little extra gasolene is desirable and it will therefore be obvious how this extra gasolene may be furnished, due to the condition existing immediately preceding such acceleration. A complete mixture is 20 assured on low running and any accumulation during a period of rest will be utilized in starting the engine.

The dash adjustment which has been described is used on starting where it is desired to cut down the amount of air entering 25 the carbureter, this being done by confining the entry of air to the capacity of the main air inlet. In the starting operation the entry of air may be further restricted by 30 means of the valve 3^a which may be closed down to limit the entry of air to that passage through the clearance around it, but which is wide open in subsequent running.

For a certain range of suctions, after the 35 starting function has been fulfilled, the main fuel inlet and air inlet provide the proper mixture. However, it is well known that as the suctions are further increased, the mixture produced by the main air and fuel inlets alone would be too rich, and, 40 therefore, diluting air or a diluting mixture is admitted from the auxiliary air inlet or the auxiliary air inlet and the auxiliary fuel inlet. The auxiliary air valve is oper-

ated by suctions, but the influences which 45 tend to hold it upon its seat are such that it does not respond until after a certain degree of suction has been attained.

I refer now to Fig. 3 where it will be seen that I provide concentric nozzles instead of 50 openings in the Venturi tube. It will be seen that the nozzle 9 is surrounded by another nozzle h , the interior of which is connected by means of one or more passageways 55 l , with the carbureting chamber in the manner that the openings h connect therewith, as has been described. The action is the same in kind as that which has been described. It will be seen that in most cases the movement of the gasolene is due to a difference in pressure in the carbureting chamber compared with that in the Venturi tube. There is a slight difference in degree, however, due to the fact that the movement of mixture out of the annular nozzle is concentrated close about the interior nozzle and aspiration from the interior nozzle may be materially assisted under certain circumstances in this way.

I claim as new and desire to secure by Letters Patent:

In a carbureter, a carbureting chamber, a mixture outlet therefor, a throttle valve in said mixture outlet, an air inlet, a Venturi tube leading from said air inlet to said carbureting chamber, a main fuel nozzle feeding into said Venturi tube from a source of supply, and a passageway leading from a point in said carbureting chamber below said throttle where liquid fuel may collect 75 to an auxiliary fuel nozzle feeding into the zone of lowest pressure in said Venturi tube, said auxiliary nozzle being independent of the supply of fuel to said main fuel nozzle.

In witness whereof, I hereunto subscribe 80 my name this 10th day of July A. D. 1915.

CHARLES W. STIGER.
